US00D732555S

(12) **United States Design Patent**
Schoger et al.

(10) **Patent No.:** **US D732,555 S**
(45) **Date of Patent:** **** Jun. 23, 2015**

(54) **DISPLAY SCREEN WITH GRAPHICAL USER INTERFACE**

(75) Inventors: **Stephen Schoger**, Waterloo (CA);
Hanan G. Ayad, Kitchener (CA)

(73) Assignee: **D2L Corporation**, Kitchener, Ontario (CA)

(**) Term: **14 Years**

(21) Appl. No.: **29/427,549**

(22) Filed: **Jul. 19, 2012**

(51) **LOC (10) Cl.** **14-04**

(52) **U.S. Cl.**

USPC **D14/486**

(58) **Field of Classification Search**
